United States Patent Office

Des. 216,636
Patented Feb. 24, 1970

216,636

MARGARINE TUB OR SIMILAR ARTICLE

Lee Vitale, New York, N.Y., assignor to Lever Brothers
Company, New York, N.Y., a corporation of Maine

Filed Dec. 5, 1968, Ser. No. 14,794

Term of patent 14 years

Int. Cl. D9—04

U.S. Cl. D9—220

FIGURE 1 is a developed view of the side wall of a margarine tub or similar article showing my new design; and

The bottom is substantially plain and unornamented.

I claim:

The ornamental design for a margarine tub or similar article, as shown and described.
